UNITED STATES PATENT OFFICE.

ERNST SALZMANN, OF SOLOTHURN, SWITZERLAND.

MARKING DEVICE.

Application filed July 28, 1924, Serial No. 728,763, and in Germany August 6, 1923.

This invention relates to improvements in marking devices, and has particular reference to an instrument used by draftsmen to mark or locate points which are subsequently utilized for describing arcs and circles and determining measurements.

When making a drawing either on plain or lined paper, it often becomes necessary to repeatedly use a particular point on the sheet as a center for describing arcs and circles and determining measurements. These points, which are customarily made with a compass, are some times difficult to locate with the result that considerable time is lost.

15 In accordance with the present invention the above disadvantage is overcome by the provision of an instrument which may be readily manipulated to make a point by pricking the drawing surface and at the same time marking or locating said point by means of a marking cartridge so that the point will at all times be readily discernible. The device may also be provided with a sharpening tool by means of which the marking edges of the cartridge may be kept sharpened.

The inventive idea is illustrated in the accompanying drawing which shows preferred modifications.

30 In the drawing—

Fig. 1 is a longitudinal section showing the instrument in position for forming a point;

Fig. 2 is a similar view showing the parts in position for marking said point;

35 Figs. 3 and 4 are side elevations of the instrument taken at right angles to Figs. 1 and 2, respectively.

Figs. 5, 6 and 7 are cross sections on the lines 5—5, 6—6 and 7—7, respectively, of 40 Fig. 1.

Figs. 8 and 9 are partial elevations of a second form of construction in the pricking and marking positions.

45 Figs. 10 and 11 are sections of the marking cartridge, Fig. 10 being taken on the line 10—10 of Fig. 1.

Fig. 12 shows the sharpening tool without protecting cap;

Fig. 13 is a protector screwed on the instrument, and

Fig. 14 is an enlarged view of the mark made by the instrument.

55 A sleeve 4 is bifurcated at its lower end for a major portion of the length thereof and slidably mounted in the bifurcated end of

said sleeve is a slider 5 of greater width than the sleeve as shown in Figure 6 to permit the operator of the device to grasp the projecting edges of the slider and thus force the same downwardly. The lower portion 60 of the slider 5 is slotted, as indicated at 5', to receive the head 3 to which the spindle 2 is attached so as to allow for the vertical movements of the slider when the same is depressed and subsequently released. The head 65 3 constitutes a part of the sleeve 4 and simply provides a bridge or connecting piece at the lower end of said sleeve which extends through the slot 5' as shown in Figure 5. The lower extremity of said slider terminates 70 in a head 6 which has a bearing on the spindle 2 and which has a portion 6' projecting upwardly into the lower bifurcated end of the sleeve 4.

The head 6 is split at its lower end to form 75 a holding portion 7 for receiving the upper end of a tubular marking cartridge 8 fitted over the spindle 2 and preferably made of some colored material such as graphite or chalk, the lower end of said cartridge being 80 tapered to form a sharp marking edge which will make a distinct circle about the point of the pricking needle when the latter is engaged with a drawing surface and the slider subsequently depressed to contact the lower end of the cartridge with said surface and thereafter given a slight rotation.

In order to retain the slider 5, and consequently the cartridge or marker 8, in a retracted or normal position, as shown in Figures 1 and 3, the sleeve 4 carries a disc 11 through which extends the lower end of a rod 10 secured to the upper end of the slider 5, said rod terminating at its upper end in a head 10' in the form of a piston. Interposed between the head 10' and the disc 11 and encircling the rod 10 is an expandable coil spring 9 which normally bears against the head 10' to retain the same in its uppermost position with the result that the slider 5 and the cartridge 8 are also yieldably held in their normal retracted positions. However, when the slider 5 is depressed the rod 10 is carried with it and operates, through its head 10', to contract and place under tension the spring 9 as shown in Figure 2 and when said slider is released, after making a mark on the drawing surface about the needle point 1, said spring will expand and thus again restore the various parts to normal. 110

At the time when the cartridge is engaged with the drawing surface, the device may be given a rotation so that the mark made by the cartridge will be more distinct.

5 The second form of construction in Figs. 8 and 9 differs from the construction above described only in the arrangement of the lower end of the slider and of the needle holder.

10 The spindle 12 is loosely mounted on the spindle 2 for longitudinal movement relative thereto and has its threads engaged with internal threads formed in the head 6. The upper end of the spindle 12 carries a disc or 15 enlargement 13 which is interposed between the lower end of the head 3 and the head 6, its engagement with the latter head preventing complete detachment of the spindle 12 therefrom. With the parts in the normal 20 position shown in Figure 9, a downward movement of the slider 5 carries the spindle with it, without turning of said spindle, until the marker 8 engages the drawing surface, as shown in Figure 8. At this time the disc 25 13 is still in engagement with the head 6, but upon further pressure being applied to the slider 5 to move it to the position shown in Figure 8, the spindle 12, being no longer capable of downward movement, will be 30 turned relative to the spindle 2 by reason of the screw threads in the head 6, thereby causing the marker 8 to make a circle about the point formed by the spindle 2. Upon removal of the instrument from the drawing 35 surface and consequent retraction of the slider 5, its head 6 will draw the spindle 12 back to its normal position shown in Figure 9.

The sharpening tool shown in Figs. 12 and 40 13 consists of a hand-piece 14 which is provided with a toothed head 15 for sharpening the outer edge of the end of the cartridge and with a sleeve 16 with a toothed edge for sharpening the inner edge of the end of the cartridge.

45 This sharpening tool may be screwed into the upper end of the sleeve 4 and be protected by a cap 17 screwed over the top of the sleeve and thus protected as shown in Fig. 13, but the instrument could be provided with such a sharpening tool, the sharpening tool being disposed in a separate cap.

Having now particularly described and ascertained the nature of my said invention and in what manner the same is to be performed, I declare that what I claim is:

1. A marking instrument for use in making drawings, including a spindle having a pricking needle adapted to form a point in a drawing surface, a sliding member having a bearing on said spindle and movable along the same, a marker carried by said sliding member and movable therewith from a normally retracted position into engagement with said drawing to form a mark thereon adjacent the point formed by said needle,

and means for normally retaining said marker in its retracted position.

2. A marking instrument for use in making drawings, including a spindle having a pricking needle adapted to form a point in a drawing surface, a sliding member movable along said spindle from a retracted position and provided at its lower end with a split head, a marker mounted in said head and movable with said sliding member from a normally retracted position into engagement with said drawing surface to form a mark thereon adjacent the point formed by said needle, and means for normally retaining said marker and sliding member in their retracted positions.

3. A marking instrument for use in making drawings, including a spindle having a pricking needle adapted to form a point in a drawing surface, a sliding member movable along said spindle, a marker carried by said sliding member and movable therewith from a normally retracted position into engagement with said drawing surface to form a mark thereon adjacent the point formed by said needle, a sleeve for said sliding member having a bifurcated end forming guides for receiving and supporting said member, and means enclosed by said sleeve for normally retaining said marker in its retracted position.

4. A marking instrument for use in making drawings, including a spindle having a pricking needle adapted to form a point in a drawing surface, a sliding member movable along said spindle and terminating at one end in a split head, a marker mounted in said split head and movable with said sliding member from a normally retracted position into engagement with said drawing surface to form a mark thereon adjacent the point formed by said needle, a sleeve for said sliding member having a bifurcated end forming guides for receiving and supporting said member, and means enclosed by said sleeve for normally retaining said marker in its retracted position.

5. A marking instrument for use in making drawings, including a spindle having a pricking needle adapted to form a point in a drawing surface, a sliding member having a bearing on said spindle and movable along the same, a marker carried by said sliding member and movable therewith from a normally retracted position into engagement with said drawing surface to form a mark thereon adjacent the point formed by said needle, means for normally retaining said marker in its retracted position, and means for causing rotation of said marker after the sliding member has been moved along said spindle to engage the marker with said surface.

In testimony whereof I affix my signature,
ERNST SALZMANN.
